JONAS H. WIEST, OF INDIANAPOLIS, INDIANA.

CISTERN OR CATCH-BASIN CLEANER.

1,021,960.

Specification of Letters Patent.

Patented Apr. 2, 1912.

Application filed July 5, 1910. Serial No. 570,235.

To all whom it may concern:

Be it known that I, JONAS H. WIEST, a citizen of the United States, residing at Indianapolis, in the county of Marion and State of Indiana, have invented certain new and useful Improvements in Cistern or Catch-Basin Cleaners; and I do declare the following to be a full, clear, and exact description of the invention, reference being had to the accompanying drawings, and to the letters and figures of reference marked thereon, which form a part of this specification.

This invention relates to apparatus for removing sedimentary matter from rain-water cisterns, catch basins, or water tanks, the invention having reference particularly to apparatus whereby cisterns or the like may be cleaned in a measure automatically, and whereby the sediment may be removed by manual operations at will.

The object of the invention is to provide improved relatively cheap apparatus for cleaning cisterns, or the like, as frequently as they become full of water and overflow, and whereby more thorough cleaning operations may be carried on at pleasure and particularly at times when the water is at a low stage, a further object being to provide an improved cistern cleaner that will be adapted to be operated readily and which at times will operate automatically without requiring attention.

With the above-mentioned and other objects in view, the invention consists in an improved cistern or catch basin cleaner comprising certain novel features of construction, and in novel parts and combinations and arrangements of parts, as hereinafter particularly described and then pointed out in the accompanying claims.

Referring to the drawings, Figure 1 is a vertical central sectional view of a cistern built in the ground and having the improved cleaning apparatus connected therewith; Fig. 2, a vertical central sectional view of one of the parts of the cleaner; Fig. 3, an inverted plan view of the part shown in the preceding figure; Fig. 4, a fragmentary vertical central sectional view of the complete cleaning apparatus; Fig. 5, a top plan of one of the parts of the apparatus; and Fig. 6, a fragmentary vertical sectional view of the principal parts of the apparatus. Similar reference characters in the different figures of the drawings indicate corresponding elements or features of construction referred to herein.

In the drawings the numeral 1 indicates the bottom, 2 the side, 3 the top, and 4 the neck of the cistern; 5 indicating the inlet pipe through which water may pass into the cistern; 6, the overflow pipe for carrying off the surplus water when the cistern is approximately full, and 7 indicating a pipe through which water may be drawn from the cistern by a pump in the usual manner.

The improved cleaning apparatus comprises a bell-shaped annular base 8 having notches 9 in the edge of the wall of its flared larger end which rests on the bottom 1 of the cistern, the notches permitting water and sedimentary matter to enter the base. The upper portion of the base has a neck 10 at the lower end of which is a shoulder 11 for supporting a pump, the base having also a tube 12 which projects from the upper smaller portion of the base downward nearly to the bottom of the larger portion of the base, the neck 10 and the tube 12 forming a continuous passage upward through the base, the passage preferably being of less diameter at its lower end than at its upper end and adapted to form a part of the pump. The base preferably has a number of bolt-holes 13, 14, 15, and also an annular seat 16 facing upward on the exterior of the larger end portion thereof but as will hereinafter appear either the holes or the seat may not be required. An annular bell-shaped or flared pipe-end 17 is provided which has a greater diameter than the base 8 and extends about the base in such a position as to be slightly above the bottom 1 of the cistern to form an annular passage around the exterior of the base, the pipe-end preferably having projections 18, 19, 20, on the inside of the larger end thereof that rest on the seat 16, the upper portion having a neck 21 thereon to which is connected a vertical pipe 22 having a lateral outlet pipe 23 that is connected with the overflow pipe 6 of the cistern. The pipe-end 17 preferably has bolt-holes 24, 25, 26, therein to receive bolts 27 whereby the pipe end may be secured to the base 8 if desired, and in case the projections 18, 19, 20, are omitted the bolts have spacing thimbles 28 thereon extending from the base 8 to the pipe-end 17 for holding the two parts in the desired relative positions.

When the base is inserted into an empty cistern the pipe-end may be readily placed thereon separately and need not be bolted to the base, but it may be desirable to bolt 5 the two parts together when they are to be placed in an old cistern well filled with water. A pump barrel 29 is provided that has an annular valve seat 30 in the lower portion thereof on which a foot valve 31 10 is mounted in any suitable manner, and the pump barrel has an extension 32 thereon adapted to fit over the neck 10 of the base 8 removably, the upper end portion of the pump barrel having a discharge spout 33 15 thereon. A pump rod 34 is inserted in the pump barrel and has a leather bucket or sucker 35 on its lower end and an operating handle 36 on its upper end, the pump being constructed substantially like 20 the well known form of bilge-water pumps.

In practical use the pump may be ordinarily omitted from the apparatus and kept in readiness for use when desired, and ordinarily in the absence of the pump when the 25 cistern becomes full of water the surplus water will seek an outlet and pass through the notches 9 and up through the tube 12, and between the base and the pipe-end 17, the water carrying with it much of the sedimentary matter out through pipe 22 and the branch pipe 23 into the drain pipe 6, which operations will be repeated each time 30 the cistern becomes replenished with water, so as to raise the level of the water above 35 the overflow pipe, the pressure of the water in the cistern causing a rapid flow up through the pipe 23, so as to remove much of the sediment from the bottom of the cistern, leaving the bulk of the water clean and 40 in good condition for use. During scarcity of rain the cistern may be filled by means of a hose, and if the cistern be nearly empty a rod may be inserted through the pipe 22 and down through the base to loosen or stir 45 the sediment, or the hose may be let down for the same purpose and the matter loosened by means of a stream of water directed against the bottom of the cistern. When 50 it is desired to clean the cistern thoroughly 55 the pump barrel should be connected to the neck 10 of the base and the pump operated in the usual manner; and it may be desirable while pumping to throw a stream of water onto the bottom of the cistern either outside of the pipe 22 or between the pump barrel and the inner side of the pipe. If 60 desired, of course, the pump may be allowed to remain permanently in the cistern, in which case the sediment will automatically 65 pass out through the pipe 22 around the pump barrel, and the pump may then be operated occasionally with good results.

It will be understood that in the absence 65 of the pump, the cross-sectional area of the pipe 22 is greater than the combined area

of the passages in and around the upper portion of the base 10, so that the water and sediment may pass rapidly through the relatively short passages into the longer and larger pipe, circulation and outflow of sedimentary matter being induced by the tube 70 12 which enlarges upward, the two bell-mouthed parts covering considerable area and contributing to the improved results.

Having thus described the invention, what 75 is claimed as new, is—

1. A cistern cleaner including an annular flaring base having notches in the edge of the larger end thereof, the smaller end being adapted to have a pump-barrel connected thereto, and a pipe having a flaring pipe-end on one end thereof that extends about the flaring base at a distance therefrom, to form passages through and also around the base to the pipe, the opposite 80 end portion of the pipe having a lateral branch-pipe thereon.

2. A cistern cleaner including an annular flaring base having notches in the edge of the larger end thereof, the smaller end being adapted to have a pump barrel connected thereto, and having also a tube therein extending from the smaller end toward the larger end thereof, and a pipe having a flaring pipe-end on one end thereof that 90 extends about the flaring base at a distance therefrom, to form passages through and also around the base to the pipe, the opposite end portion of the pipe having a lateral branch-pipe thereon.

3. A cistern cleaner including an annular flaring base having notches in the edge of the larger end thereof, the exterior of the base having an annular seat thereon facing toward the smaller end of the base to receive the end of a pump-barrel, a flaring pipe-end having projections on the inner side of the larger end thereof engaging the annular seat, the pipe-end extending about the base, and a pipe connected to the pipe-end and having a lateral branch-pipe thereon.

4. A cistern cleaner comprising an annular flaring base having notches in the edge of the larger end thereof, and having also a tube therein extending from the smaller end toward the larger end thereof, a flaring pipe-end extending about the base at a distance therefrom and supported by the base, a pipe connected to the smaller end of the flaring pipe-end and having a lateral branch-pipe thereon, and a pump comprising a pump-barrel extending through the pipe and connected to the smaller end of the base and thereby forming connection 110 120 125 with the tube.

5. A cistern cleaner comprising an annular flaring base having notches in the edge of the larger end thereof, and having also a tube therein extending from the smaller 130

end toward the larger end thereof, a flaring pipe-end extending about the base and secured thereto at a distance therefrom, a pipe connected to the smaller end of the flaring pipe-end and having a lateral branch-pipe thereon, a pump-barrel in the pipe and connected to the smaller end of the base and thereby forming connection with the tube, the pump-barrel extending 10 beyond the pipe and having a spout there-

on, a foot-valve mounted in the pump-barrel, a pump-rod in the pump-barrel, and a bucket on the pump-rod.

In testimony whereof, I affix my signature in presence of two witnesses.

JONAS H. Wiest.
